United States Patent Office

Des. 183,647
Patented Oct. 7, 1958

183,647

PLAY VEHICLE

Darwin W. Clay, Wyomissing, Pa.

Application September 25, 1957, Serial No. 47,848

Term of patent 14 years

(Cl. D34—15)

Fig. 1

Fig. 2

Fig. 1 is a top perspective view of a play vehicle showing my new design.

Fig. 2 is a bottom perspective view thereof.

The dominant features of the new design are shown in solid lines in the drawing.

I claim:

The ornamental design for a play vehicle, as shown and described.
